Term of patent 14 years

(Cl. D85—6)

FIG. 1

FIG. 2

FIG. 3

FIG. 4

FIG. 1 is a perspective view of a cigarette showing our new design.

FIG. 2 is a fragmentary developed plan view of the cigarette shown in FIG. 1.

FIG. 3 is a view similar to FIG. 2 wherein the wavy band is more sinuous,

FIG. 4 is a view similar to FIG. 2 wherein the wavy band is formed of separately printed lines,

FIG. 5 is a view similar to FIG. 2 wherein the wavy band is angular, and

FIG. 6 is a view similar to FIG. 2 wherein the waves forming the band are more widely spaced.

The essential feature of our design resides in the combination on a cigarette having a contrastingly colored tip of a narrower wavy band of a third color separating the tip from the balance of the cigarette, substantially as shown.

We claim:

The ornamental design for a cigarette, as shown and described.
